UNITED STATES PATENT OFFICE.

ISAAC FRANCES TAYLOR, OF LONDON, ENGLAND.

FOG SIGNALING APPARATUS FOR RAILWAYS.

SPECIFICATION forming part of Letters Patent No. 436,880, dated September 23, 1890.

Application filed October 22, 1889. Serial No. 327,830. (No model.)

To all whom it may concern:

Be it known that I, ISAAC FRANCES TAYLOR, a subject of the Queen of Great Britain and Ireland, and residing at Manor Park, in the county of Essex, England, have invented certain Improvements in Fog Signaling Apparatus for Railways, of which the following is a specification.

This invention for improvements in fog signaling apparatus for railways relates to means or apparatus for the purpose of enabling the signal-man, when the ordinary semaphore signal-arm is placed at "danger," to also place a detonating signal in position to be exploded by a hammer or striker actuated by the passing train or by the wheels of the train, thus dispensing with the services of fogmen during fogs, and has for its objects to provide an improved construction of reservoir for holding the supply of detonators and an improved arrangement of mechanism for feeding the said detonators from the reservoir to the position for being exploded when the semaphore-arm is put in its "danger" position, and, should the detonator previously fed forward be unexploded, of returning it to the reservoir and of removing the case of a detonator exploded by a passing train and for actuating the hammer or striker.

In fog signaling apparatus constructed according to my invention when a train approaches the semaphore-signal at "danger" it passes over and depresses a counterweighted pedal-lever, actuating, by means of a cam and detent, a hammer-lever, which forces a detonator on the lever into contact with an anvil and explodes it, the pedal-lever being retained in its lowered position and the hammer-lever returning by its own weight, the detonator-case being caught by prongs and guided out of the apparatus. When the signal is lowered to "safety," the train passes on, and on the signal being again put at "danger" a fresh detonator is fed onto the hammer-lever, the detonator previously on the lever, if unexploded, being again passed into the reservoir. When the signal is lowered to "safety," the pedal-lever is lowered out of the way of a passing train, the detent actuating the hammer-lever being first moved out of the way, and on the signal being again put to "danger" the pedal-lever is raised, and as soon as the

cam actuating the detent has passed it the detent is returned to position for actuating the hammer.

In the accompanying sheets of illustrative drawings, Figure 1 is a plan of fog signaling apparatus constructed according to my invention, and Fig. 2 is an elevation of the same. Fig. 3 is a longitudinal vertical section, to an enlarged scale, showing the mechanism for actuating the hammer-lever and for holding and feeding the detonators; and Fig. 4 is an elevation showing the pedal-lever and the manner of connecting it with the other mechanism. Fig. 5 is a plan view of the device, parts being broken away to more fully display its construction. Fig. 6 is a plan view of the device, showing its connection with the semaphore hand-levers.

Connected to the signal hand-levers by rods 1 and working in suitable guides 2 are sliding rods 3. A projection 4 is provided on each rod 3, so that when any rod is forced forward by the signal-man a sliding bar 5 is also carried forward through a definite distance, the semaphore-signal being then at "line-clear." When the rod 3 is withdrawn, the sliding bar 5 is returned to its normal position by a T-shaped lever 6, one arm of which constantly bears against a roller 7 in a bracket 8, fixed on the bar 5, another arm carrying the adjustable counter-weight 9, and the end of the remaining arm being pivoted at 10. The bar 5 can thus be put to "line-clear" position by any one of the signal hand-levers, and returns to the "danger" position when all the said levers are in their "danger" positions.

The reservoir for the detonators is cylindrical in shape, and is provided with a number of symmetrically-arranged cylindrical compartments 11. It is attached to the base-plate 15 by means of bolts, which pass through the corners of its square base-flange, and is open at the bottom. A feed-plate 13, having openings 14 corresponding to the compartments 11 and extending to the periphery, works between the bottom of the reservoir and an annular base-plate 15. The plate 15 is square, corresponding with the flange of the reservoir, and the feed-plate 13 is circular and revolves clear of the bolts which pass through the corners of the plate 15.

On the lower side of the base of the feed-plate

13, which extends through the annular base-plate, is a series of ratchet-teeth *a*. On a central shaft 12 is a double-armed pawl 16, engaging with the ratchet-teeth *a* and forced 5 into gear by the counterweighted lever 17. The pawl 16 is actuated by the bent arm 18, attached to one end of it and the link 19. Enough spring or play is given to the link 19 to permit the said pawl to have a slight vertical motion into and out of gear with the ratchet, and in order that the pawl may be reciprocated back and forth the arm 18 is pivotally connected to the sliding bar 5 by 10 the link 19, as shown in Fig. 5. When the bar 5 is moved toward the right to the "danger" position, as shown, by the action of the signal-man, the feed-plate 13 is rotated through a space equal to the distance between the centers of two adjacent compartments 11. 15

20 In order to lock the feed-plate 13 in position, a rectangular bar 20 is arranged to slide in a hole in the base-plate 15 and take into recesses 21 in the plate 13, corresponding to the compartments 11, being forced therein by 25 means of the counterweighted lever 22, pivoted at 23, and being withdrawn therefrom by means of the bracket 24 on the sliding bar 5, acting on one arm of the lever 22. The slots 21 are narrower than the detonators, so 30 that the detonators cannot escape through them sidewise out of the feed-plate.

The pedal-lever 25 is placed close to and parallel to one of the rails, and is pivoted at one end to a fixed support 26. Its other end 35 is connected by a link 27 to a lever 28, mounted on a shaft 29, carrying a counterweighted lever 30, tending to keep the free end of the pedal-lever 25 in its raised position. An arm 31, carrying a cam or roller 32, is also mounted 40 on the shaft 29, and when the pedal-lever is depressed the cam or roller 32 acts upon a detent 33, pivoted at 34 to the hammer-lever 35, itself pivoted at one end to a fixed support 36. The other end of the hammer-lever 45 normally takes into a slot 37 in the base-plate 15, exactly opposite one of the compartments of the detonator-reservoir. This compartment *b*, unlike the others 11, is open both at the periphery of the reservoir and also at the 50 top, and is not provided with detonators. It will readily be seen that when the feed-plate 13 is rotated by the action of the signal hand-levers and the compartments 11 are full of detonators the detonator in the feed-plate 55 exactly under that compartment 11 next behind the empty compartment *b* is fed onto the hammer-lever, the other detonators in the feed-plate being advanced through one division, and that if a detonator is on the hammer-lever it is carried by the feed-plate exactly 60 under that compartment 11 next in front of the empty compartment *b*, and is fed forward at every movement of the feed-plate until it again comes onto the hammer-lever, and if 65 there is no detonator on the hammer-lever a detonator will drop from the said front com-

partment into the feed-plate to be fed toward the hammer-lever. The compartment 11 next in front of the empty compartment *b* is thus first completely emptied of its detonators, then the one next in front of it, and so on until all the compartments are emptied. When the hammer-lever 35 is operated by the cam or roller 32, the free end of the lever is forced to rise, carrying with it a detonator 70 and exploding it on the anvil 38, the cam or roller passes beyond the detent and the hammer-lever again falls, the pedal-lever being kept depressed, the cam or roller having passed beyond the detent and being prevented by it from returning. When the hammer-lever 35 falls with the detonator-case, the case is caught by prongs 39, which project within the firing-chamber *b*, and through which the lever 35 works freely and is guided 80 out of the apparatus. The prongs 39 are pivoted to a fixed support at 40, so that when the hammer is rising with a detonator they are forced out of the way by the detonator, and as soon as it has passed they 90 return by their own weight. On the explosion of the detonator the train is brought to a standstill until the semaphore-signal is lowered to "safety," when the roller 41 on the arm 42, attached to the sliding-bar 5, 95 comes in contact with the arm 31 and further depresses the pedal-lever out of the way of the wheels of the train, and by means of the link 43, pivoted to an arm on the detent 33 and to the sliding bar 5, swivels the detent out 100 of the path of its actuating cam or roller, as indicated by the dotted lines in Fig. 5. When the train has passed, the semaphore-signal is raised to "danger," and the sliding bar 5 is forced back against the projections 4 by means 105 of the T-shaped lever 6 and counter-weight 9, causing the feed-plate to advance and place a fresh detonator on the hammer-lever; also, the cam or roller passes the detent and allows the pedal-lever to rise, so as to be again capable of being actuated by a passing train, and the detent is swiveled around so as again to be in the path of the cam or roller. When the semaphore-arm is at "danger" and is lowered to "safety," the detent is moved out of the 115 way of the cam or roller, and the pedal-lever is depressed by means of the roller 32, acting on the arm 31 out of reach of the wheels of the train, so that a detonator is not exploded. Weights 44, provided with guide-rods passing 120 through the top of the detonator-reservoir, press the detonators into the feed-wheel when an empty opening comes opposite them.

What I claim as my invention, and desire to secure by Letters Patent, is—

1. In a fog-signal, the combination, with a series of bars, each connected to a separate semaphore-rod and provided with a projection, of a sliding bar automatically pressed against all the said projections and adapted 130 to cause a detonator to be placed under the anvil each time it is pushed in the opposite

direction, whereby a detonator may be placed under the anvil by any one of the said bars, substantially as set forth.

2. In a fog-signal, the combination, with a sliding bar for causing the detonators to be placed under the anvil, of a bar connected with a semaphore-bar and provided with a projection for moving the sliding bar, and a pivoted lever provided with a weight for substantially as and for the purpose set forth.

3. In a fog-signal, the combination, with a reservoir provided with a series of equidistant detonator-chambers and an open firing-chamber at one side, of a revolute feed-plate provided with open-ended holes spaced to correspond with said chambers, an anvil, and a hammer-lever working in the said open chamber in line with the anvil and supplied with detonators by the feed-plate, substantially as and for the purpose set forth.

4. In a fog-signal, the combination, with a reservoir provided with a series of equidistant detonator-chambers and an open firing-chamber at one side, of a revolute feed-plate provided with open-ended holes spaced to correspond with said chambers, an anvil, the pivoted inclined discharging-prongs projecting within said open chamber, and a pivoted hammer-lever working in the said open chamber under the said anvil and prongs, whereby the detonators may be exploded and then automatically discharged, substantially as set forth.

5. In a fog-signal, the combination, with the reservoir provided with equidistant detonator-chambers and an open firing-chamber for the hammer-lever at one side, of the feed-plate journaled on a central spindle and provided with holes for the detonators and with a face ratchet-wheel, a pawl-lever sliding vertically on said spindle and engaging automatically with the ratchet-wheel, and a sliding bar adapted to be operated by the semaphore hand-lever and operatively connected with the said pawl-lever for revolving the feed-plate, substantially as and for the purpose set forth.

6. In a fog-signal, the combination, with the feed-plate journaled on a central spindle and provided with open-ended holes for the detonators, of a sliding locking-bar engaging with the open ends of said holes, a pivoted lever normally holding said bar in engagement with one of the holes, and a hand-operated sliding bar provided with a projection for operating said lever and withdrawing the locking-bar, substantially as and for the purpose set forth.

7. In a fog-signal, the combination, with the detonator-reservoir provided with an open firing-chamber on one side, of the anvil, the pivoted hammer-lever working in said chamber in line with the anvil, the pedal-lever pivoted parallel with the rail, a rock-shaft operatively connected with said pedal-lever and

normally holding a portion of it above the rail, and an arm secured on said rock-shaft and adapted to actuate the hammer-lever when the pedal-lever is depressed, substantially as set forth.

8. In a fog-signal, the combination, with the pedal-lever pivoted parallel with the rail, of a rock-shaft operatively connected with said pedal-lever and normally holding a portion of it above the rail, an arm secured on said rock-shaft, a pivoted hammer-lever, and a detent on the hammer-lever, whereby said arm may actuate the hammer-lever through said detent when the pedal-lever is depressed and subsequently retain the pedal-lever in its depressed position, substantially as and for the purpose set forth.

9. In a fog-signal, the combination, with the hammer-lever, the detent pivoted to said hammer-lever, and the pivoted arm for actuating the hammer-lever through the detent, of a sliding bar operatively connected with the semaphore hand-lever, and a link pivotally connecting the detent with the sliding bar, whereby said detent may be moved clear of the return path of the said pivoted arm, substantially as and for the purpose set forth.

10. In a fog-signal, the combination, with a sliding bar operatively connected with a semaphore hand-lever, of a reservoir provided with a series of detonator-chambers and an open firing-chamber at one side, a feed-plate provided with holes corresponding with said chambers, an automatic stop normally preventing said feed-plate from revolving, a projection on the sliding bar for releasing said stop, and intermediate ratchet mechanism operatively connecting the feed-plate with the sliding bar, whereby said sliding bar may release the feed-plate and then partially revolve it to bring another detonator under the said firing-chamber, substantially as set forth.

11. In a fog-signal, the combination, with the pivoted hammer-lever and the anvil in line therewith, of a revolute feed-plate, a sliding bar operatively connected with said feed-plate and with the semaphore hand-lever and adapted to place the detonators between the said hammer-lever and anvil, a pedal-lever pivoted parallel with the rail, intermediate trip mechanism for actuating the hammer-lever when the pedal-lever is depressed and then retaining the said pedal-lever in its depressed position, and a link connecting the trip mechanism with the said sliding bar and permitting the pedal-lever to reassume its raised position when the said sliding bar is operated and another detonator fed between the hammer-lever and anvil, substantially as set forth.

12. In a fog-signal, the combination of the hammer-lever provided with a pivoted detent, a pedal-lever pivoted parallel with the rail and normally projecting above it, a rock-shaft operated by said pedal-lever, an arm secured on said rock-shaft for actuating the

hammer-lever and adapted to be retained by said detent after once operating the hammer-lever to hold the pedal-lever in its depressed position, a sliding bar operated by the semaphore hand-lever, a projection attached to said sliding bar for striking said arm and still further depressing the pedal-lever, and a link pivotally connecting the sliding bar with the detent, whereby the detent may be swiveled out of the return path of the said

arm on the rock-shaft, substantially as and for the purpose set forth.

In witness whereof I have hereunto set my hand in the presence of two witnesses.

ISAAC FRANCES TAYLOR.
